FRANK MEAD VAN SICKLE, OF TRENTON, NEW JERSEY, ASSIGNOR OF ONE-THIRD TO
MARY A. VAN SICKLE, OF BRANCHVILLE, NEW JERSEY

WATER GATE AND HOSE CONNECTION

Application filed May 17, 1929. Serial No. 363,957.

This invention relates to a water gate and hose connection.

The object of my invention is the construction of a very simple and efficient water gate or valve device, applied to a standard water plug, whereby the flow of liquid to a hose can be easily controlled.

Another object of the invention is the construction of a valve device used upon an outlet of a water plug, and which device can be quickly and easily manipulated for controlling the flow of water through said outlet.

With the foregoing and other objects in view, my invention comprises certain novel constructions, combinations and arrangements of parts as will be hereinafter fully described, illustrated in the accompanying drawings, and more particularly pointed out in the appended claims.

20 In the drawings:

Figure 1 is a view in side elevation of a water plug with my water gates or valve devices applied thereto, and showing in longitudinal section a hose to be applied thereto.

25 Figure 2 is an end view of the apparatus, showing the cap removed.

Figure 3 is a vertical sectional view taken on line 3-3, Figure 4, and looking in the direction of the arrows.

30 Figure 4 is a sectional view taken on line 4-4, Figure 3.

Figure 5 is a perspective view of one of the valve sections.

35 Figure 6 is a perspective view of one of the caps.

Referring to the drawings by numerals, 1 designates the water plug, which is provided with the two horizontal outlets 2. The plug 1 is provided with the wheel 3 that controls the ordinary valve means within the plug, which valve means normally closes the water main, but when said valve means is open, water is free to pass out the outlets 2. Now, to prevent such passage, I have provided each outlet with a similarly constructed water gate or valve device 4. This valve device 4 comprises a heart-shape sectional valve casing 5. This casing 5 includes the rear plate 6 integral with and forming a part of the outlet 2. A front plate 7 is integral with and forms

a part of the outlet (Fig. 4), and between plates 6 and 7 is the central plate 8, which plate 8 is provided with annular flanges 9 and through the edges of plates 6 and 7 and flanges 9 extend the fastening bolts or screws 55 10. A right hand valve section 11 and a left hand valve section 12 is placed between plates 6 and 7 and fill the space therebetween. The valve section 11 is preferably provided with a pair of upwardly extending apertured ears 60 13 and also with a longitudinally extending, inwardly projecting tongue 14, which tongue fits into the longitudinally extending groove 15 formed on the inner edge of valve section 12. 65

On valve section 12 is preferably a single ear 14^a that is positioned between ears 13; a pin 14^b is placed in the registering apertures of ears 13 and 14^a, pivotally connecting the sections 11 and 12 together within the valve casing 4. Each section 11 and 12 is provided with an upstanding integral annular handle 15 and on the outer end of each handle is fixed a grip 16 for enabling the operator to readily manipulate the valve 70 sections for opening and closing the same within the casing 4. The handles 15 are positioned in an opening 17 in the top of the valve casing. The valve sections fit snugly the interior of the casing, thereby closing the 75 opening 17, so that the leakage from the valve is of negligible character and does not affect materially the flow from the main valve outlet. Each handle is angular to allow of sufficient play, one with respect to the other, 80 during the swinging of the handles for opening and closing the valve. The peculiar heart shape casing 4 is required, in that the substantially semi-circular disc-like valve sections 11 and 12 require a "heart-shape" casing 85 to accommodate their swinging movement from a closed to an open position and vice versa. 90

On the outer end of each outlet 2 are flanges 18. Each flange is provided with an aperture 95 19. It is desired to connect hose 20 (Fig. 1) to the outlet, and I accomplish this by forming a head 21 on the hose, with inwardly extending flanges 22; flanges 22 pass between the flanges 18, and then by turning the hose 100

slightly, said flanges 22 lock behind the flanges 18 holding the hose on the water plug. By this structure, a quick connection is provided between the water plug and the hose.

5 When the water plug is not in use, I close the outlets 2 by means of caps 23, connected permanently to the outlets by chains 24. Each cap comprises a body having inwardly extending flanges 25. Each flange 25 is provided with an aperture 26, which is true of the flanges 22 of head 21 of the hose. Therefore, when the apertures on the flanges 22 of the hose or flanges 25 of the cap register with the apertures 19 or flanges 18, an ordinary fastening means can be placed in these registering apertures, holding the parts against accidental displacement.

10 The handles 15 extend outwardly from the curved outer edges of the valve sections, whereby a sufficient leverage is efficiently obtained for swinging the valve sections on the pivot pin 14^b. Therefore, when the valves in the casings 4 are closed, the main valve of the water plug 1 can be opened and then 15 as soon as the operator attaches the hose, the valve in the casing 4 can be quickly operated for allowing the water to flow through the hose.

15 When the caps 23 are on the outlets, they 20 form a tight closure, as well as preventing an unauthorized person from tampering with the valve sections in the heart-shape valve casings 4.

20 While I have described the preferred embodiment of my invention and illustrated the same in the accompanying drawings, certain minor changes or alterations may appear to one skilled in the art to which this invention relates during the extensive manufacture 25 of the same, and I therefore, reserve the right to make such alterations or changes as shall fairly fall within the scope of the appended claims.

25 What I claim is:

1. In a device of the class described, the combination of a heart-shape sectional casing, swinging valve sections provided with interlocking ears pivotally mounted in said heart-shape sectional casing, and manually 30 operable angular handles crossed in one position of the valve extending into said sectional casing and connected to the outer edges of said valve sections below said ears.
2. In a device of the class described, the 35 combination of an inner plate, and outer plate, a central filler plate between said inner and outer plates provided with parallel outwardly extending flanges on its edges and an opening in its top, fastening means extending through said inner and outer plates and into said parallel flanges only, a pair of valve sections pivotally mounted at their upper ends upon said inner and outer plates only 40 below said opening in said filler plate, angular handles secured to said valve sections on

their edges between the upper and lower ends of said valve sections and overlapping in one position of the valve, said handles extending through and working in said opening of the filler plate.

70 In testimony whereof I hereunto affix my signature.

FRANK MEAD VAN SICKLE.
